UNITED STATES PATENT OFFICE.

SARAH F. HARDY, OF MINNEAPOLIS, MINNESOTA.

BUTTONHOLE-OPENER.

SPECIFICATION forming part of Letters Patent No. 612,416, dated October 18, 1898.

Application filed June 10, 1897. Serial No. 640,141. (No model.)

To all whom it may concern:

Be it known that I, SARAH F. HARDY, of Minneapolis, Hennepin county, Minnesota, have invented certain new and useful Improvements in Devices for Opening Buttonholes in Starched Articles, of which the following is a specification.

My invention relates to toilet devices; and the object of the invention is to provide means for opening the button and stud holes in starched articles and rendering the edges of the same soft and flexible preparatory to passing the cuff-button, collar-button, or shirt-stud through the same.

The invention consists generally in a middle or handle portion having tapering end portions, one being pointed and the other blunt and flattened and provided with a neck portion substantially round in cross-section and having a shoulder or disk, all as hereinafter described, and particularly pointed out in the claim.

In the accompanying drawings, forming a part of the specification, Figure 1 is a view of a cuff with the flattened end of the device thrust through one of the buttonholes. Fig. 2 is a similar view showing the buttonholes after the device has been used to open the same. Fig. 3 is a view of the shirt-bosom, showing the pointed end of the device thrust through the upper stud-hole, the lower hole being already opened. Fig. 4 is a plan view of the device. Fig. 5 is a side view of the flattened end of the same. Fig. 6 is a sectional view on the line xx of Fig. 4. Fig. 7 is a sectional view on the line yy of Fig. 4.

In the drawings, 2 represents a link-cuff of the ordinary style provided with the usual buttonholes 3, through which the cuff-button 40 is passed to hold the ends of the cuff together. The device for opening the holes may be made of any suitable material—preferably wood, silver, or celluloid, though it may be made of bone or ivory, if desired—and comprises a middle or handle portion 4, to be clasped by the fingers of the operator when in use, and tapering end portions 5 and 6, one of which terminates in a sharp point 7, provided near the point with a shoulder or flange 8, which 45 limits the movement of the pointed end when the same is thrust through the stud-hole in the shirt-bosom. The opposite end 6 of the

device is preferably provided with a flattened portion 9, substantially elliptical in cross-section and of sufficient width to separate the 55 stiff starched edge of the buttonhole in a collar or cuff when the device is thrust through the same. Between the flattened portion 9 and the handle portion 4, I provide a neck 10 which is substantially round in cross-section 60 and which serves to form an opening to permit the button to be easily inserted into the hole when the flattened end is thrust through the buttonhole and the device is revolved, and at the same time softens and renders the 65 edges of the same flexible, thereby avoiding all danger of tearing the cuff or collar when the button is placed in position therein. The flattened end 9 is also adapted to be passed through the buttonholes in the neckband of 70 a shirt, and, if desired, the end may be moistened before being thrust through the hole in the cuff, collar, or neckband, so that the edges of the same will be made soft and flexible to permit the button to be easily inserted. 75

I have found a device of this kind almost indispensable for use in opening the buttonholes in cuffs when worn with link-buttons, particularly the style made in the form of a dumb-bell, it being almost impossible to force 80 a button of this style through the hole without tearing the cuff, and while I do not confine myself to the exact form of the device shown I have found that to produce the best results it should be made substantially in the 85 form heretofore described. If the device is made of metal, the handle portion may be provided with a space for engraving a name, or it may be otherwise suitably ornamented, thereby forming a very neat and convenient 90 article for the toilet-case.

As shown in Fig. 5, I have provided on the tapering end 6 of the device a shoulder or flange 11, which is adjacent to the neck or cylindrical portion 10. When the flattened 95 part 9 is forced through the buttonhole, the shoulder 11 will engage the surface of the article around the buttonhole, thereby limiting the movement of the tapering end 6 through the hole and preventing the tearing of the 100 cuff.

I do not claim a buttonhole-opener formed with a conical head at one end, as the same is old.

Having thus described my invention, I claim as new and desire to secure by Letters Patent—

As an article of manufacture, the button-hole-opener consisting of the middle or handle portion having one end formed with a tapering conical point having a shoulder at its base next to the handle portion and formed at the opposite end of the handle portion with a flattened portion substantially elliptical in cross-

section and between it and the handle portion with a neck substantially round in cross-section, substantially as and for the purposes described.

In testimony whereof I have hereunto set my hand this 3d day of June, A. D. 1897.

SARAH F. HARDY.

In presence of—

RICHARD PAUL,

HELEN M. G. PAUL.
